[57] CLAIM

The ornamental design for a baby bottle holder, as shown and described.

DESCRIPTION

FIG. 1 is a left side elevational view of a baby bottle holder showing my new design, the opposite side being a mirror image;

FIG. 2 is a front elevational view thereof;

FIG. 3 is a bottom plan view thereof;

FIG. 4 is a top plan view thereof; and

FIG. 5 is an exploded rear perspective view thereof. The bottle is shown in broken lines for illustrative purposes only.

FIG. 2

FIG. 5
